CHILD'S ROCKER CHAIR

Herbert G. Blinn, 9645 Wheatland Ave.,
Sunland, Calif. 91040

Filed June 10, 1974, Ser. No. 477,807

Term of patent 14 years

Int. Cl. D6—01

U.S. Cl. D6—11

FIG. 1 is an isometric view of the child's rocker chair of this invention;

FIG. 2 is a top view of the child's rocker chair of this invention;

FIG. 3 is a front view of the child's rocker chair of this invention;

FIG. 4 is a side view of the child's rocker chair of this invention;

FIG. 5 is a back view of the child's rocker chair of this invention; and

FIG. 6 is a bottom view of the child's rocker chair of this invention.

The side of the rocker not shown in FIG. 4 is a mirror image of the side shown.

I claim:

The ornamental design for a child's rocker chair, substantially as shown and described.
